BLOWPIPE

Samuel R. Oldham, Elizabeth, N. J., assignor, by
mesne assignments, to Union Carbide and Car-
bon Corporation, a corporation of New York

Application June 18, 1935, Serial No. 27,155

12 Claims. (Cl. 158—27.4)

This invention relates to blowpipes and more particularly heavy duty blowpipes employing fuel-gas at low pressure. The invention is particularly useful in connection with welding blowpipes, to which use however, the invention is not limited.

In operations wherein large quantities of fuel-gas are required under low pressure it is frequently desirable to provide blowpipe apparatus of adequate capacity in compact light and convenient form. It is also important to reduce backfiring, and to prevent flashbacks or sustained burning of gas within the blowpipe.

Prior known blowpipes of the type which employ low-pressure fuel-gas are limited to a comparatively small fuel-gas consumption range, seldom exceeding 80 cubic feet per hour. Variation of the fuel-gas consumption below this limit has heretofore been accomplished by employing injectors having different size exit orifices, and by varying the clearance between the injector head and the bore of the blowpipe. While the rate of fuel-gas consumed increases with the increase in clearance between the injector head and the blowpipe bore, the flashback resistance decreases proportionally therewith. Thus, a limit will be reached beyond which flashbacks and sustained burning in the torch will occur.

One object of the invention therefore is to provide a blowpipe of convenient size which will supply at all times a sufficient volume of low pressure fuel-gas and still possess maximum flashback resistance. Another object is the provision of such a blowpipe in a form which will insure a steady and constant flow of fuel-gas. A further object is the provision of such a blowpipe in a form which will have improved flashback resistance as well as improved means for limiting the effect of flashbacks: that is to say, a form which will insure smothering of backfires and prevent flashbacks or continued burning inside the blowpipe. Other objects will appear upon consideration of the present specification and the accompanying drawing.

The invention is shown by way of illustration in its application to a welding blowpipe in the accompanying drawing, in which;

Fig. 1 is a longitudinal mid-section through a blowpipe constructed in accordance with the invention;

Fig. 2 is a cross-section on the line II—II of Fig. 1;

Fig. 3 is a cross-section on the line III—III of Fig. 1;

Fig. 4 is a longitudinal mid-section of an in-

jector similar to that illustrated in Fig. 1 showing a modified form; and

Fig. 5 is a cross-section on the line V—V of Fig. 4, the scale being twice the scale employed in Fig. 4.

In order to realize the objects of the invention, a blowpipe is provided which is so formed or streamlined as to impose a minimum obstruction to the gas flow, and provide unrestricted back flow when temporary interruption of the flame occurs. Thus, large fuel-gas passages, a straight-way fuel-gas valve, and a long, tapered injector nozzle are ordinarily employed. Furthermore, an interchangeable injector nozzle may be provided with longitudinal slots extending inwardly from its periphery, to increase fuel-gas capacity of the blowpipe without increasing the clearance between the injector nozzle and the bore of the blowpipe. A fuel-gas chamber of substantial size is formed in the handle; the combustion-supporting gas tube extends preferably centrally through this chamber; and a plurality of fuel-gas passages, preferably equally spaced about the combustion-supporting gas tube in the front body of the handle, permit substantially unrestricted passage and even distribution of fuel gas to the nozzle.

Referring now more particularly to the drawing, it will be seen that it shows a blowpipe comprising a tubular handle H having a valve block B secured to its rear end through which block the separate gases pass before reaching the handle, and at the other end, a stem S through which the combustible mixture passes to a tip (not shown) where combustion takes place.

Fuel-gas is delivered to the valve block B through a nipple 10, whence it enters a passage 11 in the valve block which leads to a valve chamber 12, in which a valve 13 acts under control of a fluted head 14. A bore 15 connects the valve chamber 12 to the rear end of a fuel-gas chamber 16 disposed within the handle H.

The fuel-gas chamber is conveniently formed by welding a cylindrical shell 17 to the reduced section of a bell-shaped tube 18, the enlarged or bell end of which is welded or otherwise fastened to the valve block B immediately inside the end of the handle H. The forward end of the shell 17 is preferably welded or otherwise fastened to a connecting nipple 19 which will later be described.

It will be observed that the fuel-gas chamber is constructed of substantial size and is adapted to maintain a considerable volume of combustible gas within the handle. It will further be apparent that a minimum obstruction to the pas-

sage of fuel-gas from the nipple 10 to the chamber 16 is provided in the valve block, the valve 13 being of the straightway type, and it being possible to draw a straight line from the entrance 5 to the valve block through the valve chamber 12 to the fuel-gas chamber 16.

Combustion-supporting gas (usually oxygen) enters the blowpipe through a nipple 20, whence it passes to a valve 21 in the valve block B. From 10 the valve 21 the combustion-supporting gas passes through a bore 22 in the valve block. A combustion-supporting gas tube 23 has one end thereof disposed in the bore 22 and fastened therein. The combustion-supporting gas tube 23 extends 15 substantially axially through the fuel-gas chamber 16, and has its forward end fastened in an axial bore 24 in the connecting nipple 19.

The forward end of the handle H is engaged by an annular bushing 25 which extends 20 wardly thereof and which is internally threaded as at 26 to accommodate external threads 27 on the connecting nipple 19. Thus, the forward end of the handle, the forward end of the cylindrical shell 17, and the forward end of the combustion-supporting gas tube 23 are all connected 25 by the connecting nipple 19 and the annular bushing 25.

The stem S is connected with the handle H by means of a hollow nut 28, having internal threads 30 thereon which coact with external threads 30 on the connecting nipple 19. The hollow nut 28 has an internal annular shoulder 31 which bears against an external annular shoulder 32 on the stem S adjacent the end thereof. A split ring 33 35 fits into an annular depression 34 extending circumferentially of the stem S immediately beyond the forward end of the hollow nut 28 when the latter is in position and prevents the latter from moving with respect to the stem when in place.

40 The rear end of the stem S is internally enlarged and has, adjacent the rear end of the enlargement, internal threads 35 adapted to engage external threads 36 upon an injecting and mixing nozzle 37. The forward end of the injecting and mixing nozzle 37 (hereafter referred 45 to as the "injector") extends into the enlargement in the rear end of the stem, and forms therewith an annular passage as well as a mixer for mixing the fuel-gas and the combustion-supporting gas which enter the blowpipe. The injector 37 has a central passageway 38 extending axially therethrough. Surrounding this central passageway, spaced equally therefrom and extending for part of the length thereof, a plurality 50 of shorter passageways 39 are formed in the injector. The passages 39 convey the fuel-gas to, and distribute it evenly about the annular passage between the forward end of the injecting nozzle 37 and the rear end of the stem S.

60 A tubular extension 40 carries the axial passageway 38 an appreciable distance back of the surrounding passageways 39; and when the hollow nut 28 is screwed upon the connecting nipple 19 as far as it will go the beveled exterior end 41 of 65 the tubular extension 40 seats into the front end of the axial bore 24 in the connecting nipple 19. Thus, a tight fit is effected between the axial passageway 38 and the axial bore 24 in the connecting nipple 19. Similarly, that part of the 70 injector 37 which lies beyond the surrounding passageways 39 is exteriorly beveled to form a seat 42, and is pressed into a corresponding interiorly beveled seat in the forward end of the connecting nipple 19, thereby forming a tight joint therewith. Because of the shape of the

forward end of the connecting nipple 19, an annular chamber 43 is formed between the injector and the nipple with which the surrounding passageways 39 communicate.

A plurality of passageways 44 surround the axial bore 24 in the connecting nipple 19, the several passageways being preferably equally spaced from the axial bore. Communication is thus provided between the fuel-gas chamber 16 and the chamber 43 between the injector and 10 the nipple 19.

The forward end of the injector forms a head 45 disposed within and spaced from the chamber in the enlarged rear end of the stem S; and the forward end of the central passageway 38 in the 15 injector opens into this space. A constricted mixing throat 46 extends forwardly in the stem from the forward end of the head 45 to the bore 47 of the stem.

From the foregoing it will be seen that combustion-supporting gas controlled by the valve 21 20 will pass readily through the combustion-supporting gas tube 23 in the handle, thence into the axial bore in the connecting nipple 19, and thence through the central passageway 38 in the injector 25 37 from which it will be discharged in a stream from the injector into the mixing throat 46 to pass into the bore 47 of the stem S. At the same time, the fuel-gas, controlled by the valve 13, 30 will enter the chamber 16, will pass through the 35 surrounding passageways 44 into the annular chamber 43 and thence through the passageways 39 in the injector to the annular space surrounding the head 45 of the injector; after which it will pass through the gradually tapered conical 40 way to the forward end of the head 45, join the combustion-supporting gas, and be projected into the mixing throat 46.

The passageways 44 in the connecting nipple 19 and the surrounding passageways 39 in the injector 37 are constructed and arranged to offer a minimum of obstruction to the flow of the fuel-gas. Their size and number are such that free 45 passage of the fuel-gas in adequate volume may reach the mixing throat 46. The combustion-supporting gas being under higher pressure will tend to create a suction in the aspirating space surrounding the head and will thereby draw fuel-gas from the passageways 39 into the mixing 50 throat 46.

From the foregoing, it will be evident that the surrounding passageways in the connecting nipple 19 and the injector 37 afford an equally free 55 passage when back-pressure occurs in the mixing throat 46 which is in excess of the fuel-gas pressure. Thus, backfires may pass easily into the fuel-gas chamber 16. Since the combustion-supporting gas is at a higher pressure than the fuel-gas, flashbacks will not enter the injector passage 38, but will follow the path of least resistance 60 and enter into the chamber 16. However, the volume of fuel-gas contained in this chamber is large, as has been indicated, and therefore, tends to smother the backfire in the chamber 16.

Blowpipes constructed in accordance with the invention provide for unrestricted back-flow when temporary interruption of the flame occurs and produces backfires. Because of the construction of the blowpipe passages and the large fuel-gas chamber in the blowpipe handle, a backfire has 70 a free passage into a sufficient body of fuel-gas to smother it. As the back-pressure thus set up drives the fuel-gas from the mixing throat, it leaves in its place the products of combustion. As injector action, which has been momentarily in-

terrupted, is restored, the resulting mixture of oxygen from the injector and burned gases drawn into the mixing throat 46, will extinguish any flame which might remain adjacent the mixing throat, thereby tending to prevent sustained burning, or flashback in the blowpipe.

In order to increase the fuel-gas consumption range, without affecting the injector action or the flashback resistance, an injector 37 like that illustrated in Fig. 4 may be interchangeably employed. In such an injector longitudinal slots 48 are formed in the head 45' extending inwardly from the periphery thereof. Thus, additional cross section is provided to permit free passage of fuel-gas to the mixing throat, without increasing the clearance between the head 45 and the bore of stem S. The number of slots 48 may vary and the dimensions of the exit orifices of passage 38 may also vary depending upon the increased fuel-gas consumption necessary for the given work. The surrounding passageways 39 are exactly the same in this construction as in that illustrated in Fig. 1 and are equally spaced from the central passageway 38, being disposed one behind each of the longitudinal slots 48 in the head 45' (see Fig. 5). From the foregoing, it is apparent that a low-pressure blowpipe of an exceptionally wide fuel-gas consumption range may be provided by interchangeably employing injector nozzles 37 or 37' having the desired number and arrangement of passages 39 and provided with or without slots 48, in combination with an improved means for adequately limiting the effect of flashbacks.

The embodiments herein described and shown in the accompanying drawing are presented merely as examples of how the invention may be applied. Other forms differing in detail, but not in principle, from those here disclosed will, of course, suggest themselves to those skilled in the art.

I claim:

1. For use in a blowpipe, a connecting nipple having an axial passage and a plurality of eccentric passages therein, said nipple having a surface thereon contiguous to the axial passage therein for contact with a gas tube adapted for connection therewith, a coaxial surface thereon beyond the eccentric passages for contact with a second gas tube, said nipple also having thereon two coaxial threaded portions, one for accommodation of an annular bushing to which the blowpipe handle is joined, and one for accommodation of a hollow nut by which the blowpipe stem is attached.

2. For use in a blowpipe, a connecting nipple having an axial passage and a plurality of parallel eccentric passages therethrough, said nipple also having thereon an annular interiorly beveled face beyond the forward ends of the eccentric passages and an annular interiorly beveled face at the forward end of the axial passage, in combination with a nozzle having an axial passage and a plurality of parallel eccentric passages therethrough, said nozzle also having thereon an annular exteriorly beveled face beyond the rearward ends of the eccentric passages and an exteriorly beveled face beyond the rearward end of the axial passage, and means for holding said nipple and said nozzle in associated position with the beveled faces adjacent the axial passages, and the beveled faces beyond the eccentric passages respectively in engagement.

3. An oxy-acetylene blowpipe comprising oxygen and acetylene inlets; a voluminous acetylene

conducting chamber associated with the acetylene inlet; an oxygen conduit associated with the oxygen inlet; an injecting nozzle; a stem adapted to accommodate a gas mixing chamber and to support said injecting nozzle; means associated with, and adapted to connect said acetylene conducting chamber and oxygen conduit to said injecting nozzle comprising an element including means adapted to form gas-tight-forming seats with complementary means on said injecting nozzle; and means mounted on said stem and adapted to maintain said gas-tight-forming seat means in cooperative relation with said complementary means.

4. An oxy-acetylene blowpipe as claimed in claim 3, in which said element is provided with unrestricted acetylene gas passages.

5. An oxy-acetylene blowpipe as claimed in claim 3, in which said injecting nozzle is provided with unrestricted acetylene gas passages.

6. An oxy-acetylene blowpipe as claimed in claim 3, in which said injecting nozzle is provided with a head forming an annular acetylene gas passage with a portion of said blowpipe, and said head is provided with auxiliary gas passage means adapted to accommodate a relatively large volume of acetylene gas.

7. A low pressure blowpipe comprising the combination with an injector nozzle having a central passageway for discharging a stream of combustion-supporting gas; and means providing a fuel-gas aspirating space coaxial with said passageway and into which said stream of combustion-supporting gas is discharged; of streamlined fuel-gas passage means comprising a fuel-gas inlet, a backfire smothering chamber adapted to contain an ample volume of fuel gas to smother any backfire liable to occur within said blowpipe, and unrestricted parallel passages between said chamber and said aspirating space; whereby in the event of a backfire, gas backflow is unobstructed and the whole backfire freely enters said backfire smothering chamber, the products of combustion then being aspirated by the uninterrupted stream of combustion-supporting gas to extinguish any remaining flashback in the blowpipe.

8. A low pressure blowpipe comprising: an oxygen injector nozzle having an orifice for projecting a high velocity stream of oxygen; means providing an acetylene inlet, a valve, a cylindrical shell and a conical way coaxially disposed relative to said orifice; and a stem having an aspirating chamber into which said stream of oxygen is projected to aspirate acetylene through said conical way; said cylindrical shell comprising an acetylene chamber adapted to contain a sufficient volume of acetylene to smother a backfire; said acetylene inlet, valve, shell and conical way being streamlined to provide for the smooth and unobstructed forward flow of the acetylene to render the same highly responsive to the velocity of the oxygen stream projected by said nozzle; such streamlining of the acetylene flow at the same time functioning to provide for the unrestricted backward flow of the acetylene in the event of a backfire so that in such event the back pressure is absorbed by the backward flow of acetylene, and the resulting products of combustion thereafter at once flow forward as in the normal operation of the blowpipe to extinguish wholly any lingering flashback in the blowpipe.

9. A low pressure blowpipe comprising the combination with an injector nozzle having a central

passageway for projecting a stream of combustion-supporting gas; means providing a fuel-gas aspirating space coaxial with said central passageway; and means providing a gas mixing throat into which is projected the stream of combustion-supporting gas and fuel-gas; of fuel-gas passage means comprising in series a fuel-gas inlet, a valve block having a fuel-gas passage, valve chamber and bore, a bell shaped tube, a cylindrical shell, a connecting nipple having parallel passageways, an annular chamber, parallel passageways in said nozzle, a cylindrical way, and a gradually tapered conical way merging into said aspirating space; said fuel-gas passage means being adapted to provide for the unobstructed substantially straight streamlined forward flow of a large supply of fuel gas to said aspirating space in accordance with the velocity of said stream of combustion-supporting gas; said cylindrical shell providing a fuel-gas chamber of sufficient size to contain an adequate volume of fuel gas for smothering a backfire; said fuel-gas passage means at the same time providing for the unrestricted backflow of gas in the event of a backfire, in which event the backfire is smothered by the large volume of fuel gas within said fuel-gas chamber, and any lingering flashback is extinguished by the subsequent aspiration of the resulting products of combustion by said stream of combustion-supporting gas.

10. A low pressure blowpipe comprising the combination with an injector nozzle having a central passageway for projecting a stream of combustion-supporting gas; means providing a fuel-gas aspirating space coaxial with said central passageway; and means providing a gas mixing throat into which the stream of combustion-supporting gas and fuel gas is projected; of fuel-gas passage means comprising in series a fuel-gas inlet, a valve block having a valve chamber, a cylindrical shell, a connecting nipple having parallel passages, an annular chamber, parallel passages in said nozzle, a cylindrical way, and a gradually tapered conical way merging into said aspirating space; said cylindrical shell constituting a backfire smothering chamber of ample fuel gas capacity for that purpose; said inlet and said valve chamber being aligned in parallel relation with the major axis of said cylindrical shell to provide a substantially straight-through fuel-gas flow path delivering to said back fire smothering chamber; said parallel passages in said nipple, said annular chamber, said parallel passages in said nozzle, said cylindrical way and said conical way providing an unrestricted streamlined fuel-gas flow path between said backfire smothering chamber and said aspirating space; whereby in the event of a backfire, unrestricted backflow of the fuel gas causes the backfire to enter freely and be smothered by the large volume of fuel gas within said backfire smothering cham-

ber, and the resulting products of combustion are aspirated by the combustion-supporting gas to extinguish any flashback left burning adjacent said gas mixing throat.

11. A low pressure blowpipe comprising: a valve block having an oxygen bore and an acetylene passage; a tubular handle connected to said valve block; a tubular shell disposed within said tubular handle in spaced relation thereto; a bell-shaped tube connecting said shell and handle adjacent said block; an oxygen tube disposed centrally of said shell in spaced relation thereto to provide a cylindrical chamber of large size and substantial volume for the acetylene; said chamber being in line with said acetylene passage; a connecting nipple having a central oxygen passage and parallel acetylene passages; said acetylene passages being arranged in line with said cylindrical chamber, an annular bushing connecting said nipple and handle; an injector and mixing nozzle having a central oxygen passage and parallel acetylene passages; the nozzle acetylene passages and the nipple acetylene passages being in communication through an annular chamber; a stem connected to said nozzle; and a nut connecting said nipple and nozzle; said stem and the head of said nozzle being spaced to provide a cylindrical acetylene passage which merges into a conical passage; there being a throat in said stem into which the oxygen from the orifice of said injector is projected to aspirate the acetylene to provide a fuel mixture; said acetylene passages being adapted to encourage backfiring within said cylindrical chamber for the purpose of smothering the same therein, so that the subsequent forward movement of the resulting products of combustion wholly extinguishes any lingering flashback in the blowpipe.

12. A blowpipe for use with a fuel gas and a combustion-supporting gas, comprising the combination with a nozzle having a central gas passageway for discharging one of said gases, and means providing a mixing space for said fuel gas and combustion-supporting gas, said space being coaxial with said central gas passageway and into which said one gas is discharged; of a streamlined gas passage means for said other gas comprising a gas inlet, a voluminous backfire-receiving chamber adapted to contain an ample volume of such other gas to receive any backfire liable to occur within said blowpipe; and unrestricted passage means surrounding said nozzle between said chamber and said mixing space; whereby in the event of a backfire, back flow of said other gas is unobstructed and the backfire freely enters said voluminous backfire-receiving chamber, the backfire products of combustion then advancing to extinguish any remaining flashback in the blowpipe.

SAMUEL R. OLDHAM.
